1

The present invention relates to regenerative preheaters and especially to preheaters of the so-called Ljungström type. This type of preheater has a cylindrical rotor divided into sectors which are filled by heat transferring plates, said plates upon rotation of the rotor first accumulating heat from the hot gases and then, after entering the air side, delivering the accumulated heat to the air. The rotor is surrounded by an outer shell with two end plates, generally called sector plates, provided with openings for permitting the flow of gas and air into and from the preheater. In order to prevent undue leakage flow between the air and gas sides the rotor usually has been provided with radial as well as peripheral seals, bearing against the sector plates or any other suitable part of the stationary casing.

Earlier designs of such seals have generally been made as elastic elements of thin plates or the like, which by flexible bending maintain the sealing contact at all times or sometimes as rigid sealing elements, which by means of springs or the like are pressed against the surfaces against which sealing contact is desired.

In practice, however, it has proved impossible by using flexible sealing elements to maintain the sealing edges sufficiently flexible and at the same time strong enough to resist the stresses occurring for instance during soot-blowing operations. The rigid sealing elements movable by means of springs have shown the defect that their proper operation is lost after a short time on account of deposits from the gas in the form of soot, ash and tar-like compositions, such deposits occurring not only between the sealing surfaces but also between the different parts of the seal arrangement itself, resulting in lost sealing capability. Because of the uneven temperature distribution prevailing in the preheater, the devices supporting the sealing elements have shown a tendency to distort whereby the elements are separated from the sealing surfaces. By overdimensioning the springs in order to overcome every conceivable disturbance of the kind mentioned above and always secure the sealing elements in sealing position the resulting high surface pressures cause excessive wear of the sliding surfaces and consequent short life. Besides, the motor driving the rotor must be bigger due to the higher power consumption.

The sealing arrangement according to this invention consists of short elements of the rigid type, which, however, contrary to the previous

2

designs, are connected to the rotor or the casing by means of a tilt-attachment giving swinging mobility to the elements. The pressure between the elements and the sealed preheater parts may be obtained by fluid pressure difference prevailing between the different sides of the sealing line. In this way the specific surface pressure is kept as low as possible and the wear between the sealing surfaces will be small. In certain cases an increase of the contact pressure by means of springs or counterweights which simultaneously hold the sealing elements in position is of value, especially in the case of low pressure differences or if complete sealing is desired also on the cold air side.

The seals can either be double-acting or single-acting. In the first case complete sealing is obtained independently of the location of the sealing element, whether on the air or on the gas side of the preheater. When using single-acting seals, on the other hand, complete sealing is obtained only for one of the two sides.

In the following the invention will be more fully described in detail with reference to the drawings, which by way of example show some preferred embodiments of the invention.

Fig. 1 shows in cross-section, a rotary preheater provided with seals according to the invention. The section is taken along line I—I of Fig. 2.

Fig. 2 is a top plan view, broken away in part and with certain elements omitted for the sake of clarity, of the apparatus shown in Fig. 1.

Figs. 3—20 show different types of sealing arrangements.

In Figs. 1 and 2, the reference numeral 10 indicates the shell or casing of a preheater with end or sector plates 12 and 14 respectively, which are provided with openings 16 and 18 for gas and openings 20 and 22 for air flowing through the rotor. The openings are framed by channel irons to give suitable connections to the air and gas channels. The rotor 24 consists of a rotor hub 28, radial partition walls 30 and an outer shell 32, forming a plurality of sectors—generally twelve—containing the heat transferring plates 26. Said plates generally consist of specially corrugated thin plates spaced from one another in such a manner that suitable channels for effective heat transfer are formed between the plates. The plates 26 are supported by radial rods 36 at the bottom of the sectors and, at least in bigger preheaters the sectors have peripheral partition walls 38, reinforcing the rotor

and simultaneously preventing undue radial movement of the heating plates. The bars 40 secure the plates 26 against axial movement. The whole rotor is carried by a shaft 42, supported in the axial bearing 44, the casing of which is mounted in the frame work 46. The bearing 48 and the above mentioned bearing 44 guide the rotor in radial direction. The pre-heater rotor is rotating slowly by means of a motor and a co-operating gearing indicated at 50.

Generally the preheater works with air and gas flowing in counter-flow to obtain the highest possible efficiency. In the apparatus illustrated the arrow 52 indicates the direction of the gas flow and the arrow 54 the direction of the air flow. Due to the pressure drop through the pre-heater and apparatus connected therewith a pressure difference will occur between the air and the gas side, so that the pressure is highest at the air inlet opening and lowest at the gas outlet opening. Leakage flow will thus take place between the rotor and the end plate 14 from the air inlet to the gas outlet as well as between the rotor and the end plate 12 from the air outlet to the gas inlet. A third leakage flow takes place through the narrow space at the periphery of the rotor where air from the inlet opening enters the intermediate space 56 between the rotor and the stationary casing, this way flowing to the gas inlet and outlet as well as to the air outlet. In Figs. 1 and 2 the above mentioned two leakage flows occurring at the ends of the rotor are reduced by the radial seals 58 and 60 mounted on the partition walls 30, and in a similar way the leakage flow at the periphery is reduced by the peripheral seals 62 and 64.

It is of importance to reduce these leakage flows because high leakage loss means decreased preheater efficiency and increased power consumption of the air and gas fans, and thus a decrease of the overall efficiency of a power plant containing such preheaters.

Figs. 3 and 4 show a peripheral seal of the single-acting type with the sealing elements pressed against the sealing surface by the air pressure in the space 56. On the rotor shell 32 there is riveted a ring 66 acting as a contact surface for the sealing elements 68. Each element is supported by a carrier plate 72 bolted to the plate 14.

The flange of each carrier 72 is provided with a suitable number of riveted pins 74—in the case illustrated two—fitting in the corresponding holes 70 of the sealing element which is made comparatively short with its edge along the ring 66 correspondingly curved and of bulbous cross-section whereas its opposite edge is straight as is also the flange of the carrier plate 72. The holes 70 for the carrier pins 74 widen in both directions from their central sections, a shape which allows a tilting of the elements in relation to the carrier plates and thus makes it possible for the elements to slide on the rotor ring 66, even if the rotor should be distorted due to uneven temperature stresses. The plate 76, welded to the carrier plate 72, serves as a stop preventing the sealing elements from leaving the sealing rings too far and enabling the air pressure to bring them back to sealing position.

The peripheral sealing arrangements shown in Figs. 5 and 6 consist of a number of element carriers 78 bolted to the sector plates 12 and 14 respectively whereas the sealing elements 68 are hinged on the carriers 78 by means of pins 74 according to the same principles as in the above

described device. The spring 80 is guided by an arm 82 projecting from the holder 78 and presses the sealing element 68 against the rotor shell 32 with comparatively small force, while the excess pressure in the space 56 gives the essential force acting on the sealing elements of the gas side. On the cold air side the spring 80 must also overcome the whole pressure difference, counteracting the sealing pressure. The said seals may even be eliminated over this part of the periphery, the sealing effect in such case only being due to the sealing of the gas side. As in the above described arrangement the elements are characterized by a straight part at the element carriers but curved in accordance with the curvature of the rotor shell for the free sealing part.

Figs. 7-9 show another type of peripheral sealing elements 68 which are supported by the edge of the shell plate 32 of the rotor 24 in V-shaped grooves formed between each pair of abutments 84 projecting from the sealing elements. The elements are held in proper relation by means of a rod 86 and a spring 88, which connect an element in the upper sealing line with a suitable element in the lower seal. The rod 86 is movably mounted in the upper element by means of the two arms 90 and the cylindrical pin 92 and the spring 88 is correspondingly rotatably attached to the lower element. Even in this design it is of course possible to spring-load each element separately or to use weights without connecting the elements in pairs of above described.

In order to further reduce the leakage the sealing elements 68 are in this case provided with a groove 94 at one end and with a flange 93 of corresponding shape and size at the other end so that an overlapping of the peripheral spaces between the elements is obtained.

Figs. 10 and 11 show a peripheral sealing with the elements 68 supported by the V-shaped grooves formed between projections 84 extending from the elements which in turn are pressed against the flange 94 on the end plates 12 and 14 respectively due to the action of the spring 96. The latter acts between the arm 98 of the sealing element 68 and a hook 100, fixed to the shell 32.

The peripheral seals shown in Figs. 12-13 consist of short sealing elements 68 provided with projections 84, forming V-shaped supports for the elements on the rotor shell 32, said elements being preferably kept in position against the edge of the rotor shell 32 by a resilient plate 102 bolted to the rotor. Depending on the side from which the higher pressure is acting, the sealing against the stationary casing 10 occurs either at the upper end plate 12, or at a flange 104 extending from the casing 10.

In Fig. 14 the curved sealing element 68 is kept in adjusted sealing position by a counter-weight 106 acting on a lever 108 which is rigidly connected to said element and passes through a bore in the rotor shell 32, in which bore the lever is tiltable. This type of seal is especially suitable for the upper peripheral seal.

For the lower seal it is not necessary to use a counter-weight as the weight of the element itself is sufficient for urging it to sealing position. Such an arrangement is shown in Fig. 15. The curved sealing element 68 in this case is movably connected to the rotor shell 32 by a bolt 110 which according to the illustrated design runs through a suitably formed bore in the sealing element itself.

In Fig. 16 there is shown a modification of the device according to Figs. 14 and 15 which is

adaptable for preheaters with horizontal axes of rotation. A spring 112 presses the sealing element 68 against the end plates 12 and 14 respectively. The spring is supported by an arm 114 and a pin 116 fixed to the rotor shell 32, whereby the pin guides the spring which acts against a projection 118 on the sealing element.

The peripheral seal shown in Fig. 17 consists of a channel beam 120, fixed to the end plate 12, two flat irons 122 and 124 bolted to the rotor, which flat irons likewise form a channel guide groove on the rotor shell 32, and the sealing elements 68 which are shaped as short flat irons of the same curvature as the rotor shell and are inserted into the two channels. Depending on the influence of the air pressure the seals will seal against the flat iron 122 and the outer flange of the channel 120, or against the inner flange of the same and the flat iron 124. It is of importance that the width of the channels is not too small but permits a certain inclination of the sealing elements without risk of seizing.

In Fig. 18 the sealing elements 68 are fixed to the rotor by plate-like hooks 126 acting as hinges. The counter-weight 106 on the lever 108 is connected to the sealing element 68 and presses the same against the flange 128, bolted to the end plate 12.

Figs. 19 and 20 show examples of double-acting seals mounted on the radial partition walls 30, the direction of rotation being indicated by the arrow 129. The sector-formed parts of the end plates 12 and 14 are rounded or chamfered on that edge which the partition walls 30 meet when the rotor rotates, so that the curved sealing elements 130 and 132 easily can slide up on the sector plates 12 and 14 respectively. This action is also facilitated by the curved shoes 134, projecting from the leading elements 132. The upper sealing elements 130 and 132 are hinged on the common pin 138 in the same way as has already been described for the embodiment of Fig. 14, said pin being fixed to the radial partition wall 30. The lower seals are correspondingly hinged to the partition walls according to the system shown in Fig. 15. It is obvious that either the elements 130 or the elements 132 will seal independently of whether the rotor sectors turn from the air to the gas side or vice versa, which means that the overpressure, acting on the sealing elements, changes direction.

As described above all embodiments according to the invention are based on the principle that the sealing elements are hinged in such a way that the mutual movement between the sealing means is in an arcuate path. At the same time, the seals are designed and mounted in such a way that they can be cleaned easily and thoroughly by air or steam jets.

We claim:

1. In a regenerative air preheater comprising two main parts, a first part providing stationary structure comprising a cylindrical casing and end plates having inlet and outlet openings for flow of gas and air respectively, the second part comprising a rotor mounted within said stationary structure and provided with radial partitions forming compartments with heat transfer material disposed in said compartments, sealing means between the periphery of said rotor and said stationary structure comprising a plurality of rigid sealing elements pivotally mounted on one of said parts in close proximity to each other to have rocking movement relative to both of said parts and forming a substantially continuous ring, a cooperating sealing surface on the other of said

parts with respect to which said sealing elements have rocking movement, sealing means between said end plates and each of said radial partitions comprising a pair of rigid sealing members mounted on each side of each partition in opposed relation to rock in sealing contact with said end plates, and biasing means associated with certain of said sealing elements to urge the same into rocking contact with their associated sealing surfaces.

2. An apparatus as defined in claim 1 in which said biasing means comprises springs.

3. An apparatus as defined in claim 1 in which said biasing means comprises weights.

4. In a regenerative air preheater comprising two main parts, a first part providing stationary structure comprising a cylindrical casing and end plates having inlet and outlet openings for flow of gas and air respectively, the second part comprising a rotor mounted within said stationary structure and provided with radial partitions forming compartments with heat transfer material disposed in said compartments, sealing means between the periphery of said rotor and said stationary structure comprising a plurality of sealing elements pivotally mounted on one of said parts in close proximity to each other to have rocking movement relative to both of said parts and forming a substantially continuous ring, a cooperating sealing surface on the other of said parts with respect to which said sealing elements have rocking movement, sealing means between said end plates and each of said radial partitions comprising a pair of sealing members mounted on each side of each partition in opposed relation to rock in sealing contact with said end plates, and biasing means associated with certain of said elements to urge the same into rocking contact with their associated sealing surfaces.

5. In a regenerative air preheater comprising two main parts, a first part providing stationary structure comprising a cylindrical casing and end plates having inlet and outlet openings for flow of gas and air respectively, the second part comprising a rotor mounted within said stationary structure and provided with radial partitions forming compartments with heat transfer material disposed in said compartments, sealing means between the periphery of said rotor and said stationary structure comprising a plurality of sealing elements pivotally mounted on one of said parts to have rocking movement relative to both of said parts, a cooperating sealing surface on the other of said parts with respect to which said sealing elements have rocking movement, sealing means between said end plates and each of said radial partitions comprising a pair of sealing members mounted on each side of each partition in opposed relation to rock in sealing contact with said end plates, and biasing means associated with certain of said elements to urge the same into rocking contact with their associated sealing surfaces.

6. In a regenerative air preheater comprising two main parts, a first part providing stationary structure comprising a cylindrical casing and end plates having inlet and outlet openings for flow of gas and air respectively, the second part comprising a rotor mounted within said stationary structure and provided with radial partitions forming compartments with heat transfer material disposed in said compartments, sealing means between the periphery of said rotor and said stationary structure comprising a plurality of rigid sealing elements pivotally mounted on one of said parts in close proximity to each other to have

rocking movement relative to both of said parts, a cooperating sealing surface on the other of said parts with respect to which said sealing elements have rocking movement, sealing means between said end plates and each of said radial partitions comprising a pair of sealing members mounted on each side of each partition in opposed relation to rock in sealing contact with said end plates, and biasing means associated with certain of said elements to urge the same into rocking contact with their associated sealing surfaces.

7. In a regenerative air preheater comprising two main parts, a first part providing stationary structure comprising a cylindrical casing and end plates having inlet and outlet openings for flow of gas and air respectively, the second part comprising a rotor mounted within said stationary structure and provided with radial partitions forming compartments with heat transfer material disposed in said compartments, sealing means between the periphery of said rotor and said stationary structure comprising a plurality of rigid sealing elements pivotally mounted on one of said parts in close proximity to each other to have

rocking movement relative to both of said parts, a cooperating sealing surface on the other of said parts with respect to which said sealing elements have rocking movement, sealing means between said end plates and each of said radial partitions comprising a pair of sealing members mounted on each side of each partition in opposed relation to rock in sealing contact with said end plates, and biasing means associated with certain of said elements to urge the same into rocking contact with their associated sealing surfaces.

8. In a regenerative air preheater comprising two main parts, a first part providing stationary structure comprising a cylindrical casing and end plates having inlet and outlet openings for flow of gas and air respectively, the second part comprising a rotor mounted within said stationary structure and provided with radial partitions forming compartments with heat transfer material disposed in said compartments, sealing means between the periphery of said rotor and said stationary structure comprising a plurality of rigid sealing elements pivotally mounted on one of said parts in close proximity to each other to have

rocking movement relative to both of said parts, a cooperating sealing surface on the other of said parts with respect to which said sealing elements have rocking movement, sealing means between said end plates and each of said radial partitions comprising a pair of sealing members mounted on each side of each partition in opposed relation to rock in sealing contact with said end plates, and biasing means associated with certain of said elements to urge the same into rocking contact with their associated sealing surfaces.

9. In a regenerative air preheater comprising two main parts, a first part providing stationary structure comprising a cylindrical casing and end plates having inlet and outlet openings for flow of gas and air respectively, the second part comprising a rotor mounted within said stationary structure and provided with radial partitions forming compartments with heat transfer material disposed in said compartments, sealing means between the periphery of said rotor and said stationary structure comprising a plurality of rigid sealing elements pivotally mounted on one of said parts in close proximity to each other to have

to have rocking movement relative to both of said parts and forming a substantially continuous ring, a cooperating sealing surface on the other of said parts with respect to which said sealing elements have rocking movement, and biasing means associated with certain of said sealing elements to urge the same into rocking contact with their cooperating sealing surfaces.

7. In a regenerative air preheater comprising two main parts, a first part providing stationary structure comprising a cylindrical casing and end plates having inlet and outlet openings for flow of gas and air respectively, the second part comprising a rotor mounted within said stationary structure and provided with radial partitions forming compartments with heat transfer material disposed in said compartments, sealing means between the periphery of said rotor and said stationary structure comprising a plurality of sealing elements pivotally mounted on one of said parts in close proximity of each other to have rocking movement relative to both of said parts and forming a substantially continuous ring, a cooperating sealing surface on the other of said parts with respect to which said sealing elements have rocking movement, and biasing means associated with certain of said sealing elements to urge the same into rocking contact with their cooperating sealing surfaces.

8. In a regenerative air preheater comprising two main parts, a first part providing stationary structure comprising a cylindrical casing and end plates having inlet and outlet openings for flow of gas and air respectively, the second part comprising a rotor mounted within said stationary structure and provided with radial partitions forming compartments with heat transfer material disposed in said compartments, sealing means between the periphery of said rotor and said stationary structure comprising a plurality of sealing elements pivotally mounted on one of said parts to have rocking movement relative to both of said parts, a cooperating sealing surface on the other of said parts with respect to which said sealing elements have rocking movement, and biasing means associated with certain of said sealing elements to urge the same into rocking contact with their cooperating sealing surfaces.

9. In a regenerative air preheater comprising two main parts, a first part providing stationary structure comprising a cylindrical casing and end plates having inlet and outlet openings for flow of gas and air respectively, the second part comprising a rotor mounted within said stationary structure and provided with radial partitions forming compartments with heat transfer material disposed in said compartments, sealing means between said end plates and each of said radial partitions comprising a pair of rigid sealing members pivotally mounted on each side of each partition in opposed relation to rock in sealing contact with said end plates, and biasing means associated with certain of said sealing elements to urge the same into rocking contact with said end plates.

10. In a regenerative air preheater comprising two main parts, a first part providing stationary structure comprising a cylindrical casing and end plates having inlet and outlet openings for flow of gas and air respectively, the second part comprising a rotor mounted within said stationary structure and provided with radial partitions forming compartments with heat transfer material disposed in said compartments, sealing means between said end plates and each of said radial partitions comprising a pair of sealing

5 members pivotally mounted on each side of each partition in opposed relation to rock in sealing contact with said end plates, and biasing means associated with certain of said sealing elements to urge the same into rocking contact with said end plates.

11. An apparatus as defined in claim 10 in which each pair of sealing members comprises a member mounted adjacent to the upper edge of the partition and a member mounted adjacent to the lower edge of the partition, said biasing means comprising arms attached to said upper sealing members and a weight secured on each arm.

12. An apparatus as defined in claim 11 in which the weight of said lower sealing members serves to urge these members into sealing contact with the lower end plate.

13. An apparatus as defined in claim 8 in which each sealing element comprises a rigid elongated bar forming a segment of a circle, fork-like extensions on one edge of said bar disposed over an edge of the periphery of said rotor whereby said element is rockably mounted thereon, an inwardly extending flange on said stationary structure forming said sealing surface, an arm extending from said bar and resilient means secured to said arm and said rotor for urging said bar into sealing contact with said sealing surface.

14. An apparatus as defined in claim 8 in which each sealing element comprises an elongated bar forming a segment of a circle, fork-like extensions on one edge of said bar disposed over an edge of the periphery of said rotor whereby said element is rockably mounted thereon, an inwardly extending flange on said stationary structure forming said sealing surface, an arm extending from said bar and resilient means secured to said arm and said rotor for urging said bar into sealing contact with said sealing surface.

15. An apparatus as defined in claim 8 in which each sealing element comprises an elongated bar forming a segment of a circle, fork-like extensions on one edge of said bar disposed over an edge of the periphery of said rotor whereby said element is rockably mounted thereon, an arm extending from said bar and resilient means secured to said arm and said rotor for urging said bar into sealing contact with said sealing surface.

16. An apparatus as defined in claim 8 in which each sealing element comprises a rigid elongated bar, fork-like extensions adjacent to one edge of said bar disposed over an edge of the periphery of said rotor whereby said element is rockably mounted thereon, an inwardly extending flange on said casing forming said sealing surface and a leaf spring having one end secured to said rotor and the free end bearing on said bar to retain said bar on said rotor and urge the same into sealing contact with said sealing surface.

17. An apparatus as defined in claim 8 in which each sealing element comprises an elongated bar, fork-like extensions adjacent to one edge of said bar disposed over an edge of the periphery of said rotor whereby said element is rockably mounted thereon, an inwardly extending flange on said casing forming said sealing surface and a leaf spring having one end secured to said rotor and the free end bearing on said bar to retain said bar on said rotor and urge the same into sealing contact with said sealing surface.

18. An apparatus as defined in claim 8 in which each sealing element comprises an elongated bar, 75 fork-like extensions adjacent to one edge of said

bar disposed over an edge of the periphery of said rotor whereby said element is rockably mounted thereon and a leaf spring having one end secured to said rotor and the free end bearing on said bar to retain said bar on said rotor and urge the same into sealing contact with said sealing surface.

19. An apparatus as defined in claim 8 in which each sealing element comprises an elongated bar, fork-like extensions adjacent to one edge of said bar disposed over an edge of the periphery of said rotor whereby said element is rockably mounted thereon and a leaf spring secured to said rotor and bearing on said bar to retain said bar on said rotor and urge the same into sealing contact with said sealing surface.

20. An apparatus as defined in claim 8 in which each sealing element comprises an elongated bar, fork-like extensions adjacent to one edge of said bar disposed over an edge of the periphery of said rotor whereby said element is rockably mounted thereon and resilient means secured to said rotor and bearing on said bar to retain said bar on said rotor and urge the same into sealing contact with said sealing surface.

21. An apparatus as defined in claim 8 in which each sealing element comprises a rigid elongated bar arcuate in cross section, means for rockably mounting said bar on said rotor, an arm extending from said bar inwardly of said rotor and a weight secured to said arm for biasing said bar into sealing contact with said sealing surface.

22. An apparatus as defined in claim 8 in which each sealing element comprises an elongated bar arcuate in cross section, means for rockably mounting said bar on said rotor, an arm extending from said bar inwardly of said rotor and a weight secured to said arm for biasing said bar into sealing contact with said sealing surface.

23. An apparatus as defined in claim 8 in which each sealing element comprises an elongated bar, means for rockably mounting said bar on said rotor, an arm extending from said bar inwardly of said rotor and a weight secured to said arm for biasing said bar into sealing contact with said sealing surface.

24. An apparatus as defined in claim 8 in which each sealing element comprises an elongated bar, means for rockably mounting said bar on said rotor, an arm extending from said bar and a weight secured to said arm for biasing said bar into sealing contact with said sealing surface.

25. An apparatus as defined in claim 24 in which said means for rockably mounting said bar comprises an aperture in the periphery of said rotor with said arm rockably disposed in said aperture.

26. An apparatus as defined in claim 24 in which said means for rockably mounting said bar comprises a hinge connection between said bar and said rotor.

27. An apparatus as defined in claim 8 in which said sealing element comprises a rigid elongated bar arcuate in cross section and means for rockably mounting said bar on said rotor, the weight of said bar serving to retain the same in sealing contact with said sealing surface.

28. An apparatus as defined in claim 8 in which each sealing element comprises an elongated bar arcuate in cross section and means for rockably mounting said bar on said rotor, the weight of said bar serving to retain the same in sealing contact with said sealing surface.

29. An apparatus as defined in claim 8 in which each sealing element comprises an elongated bar and means for rockably mounting said bar on

said rotor, the weight of said bar serving to retain the same in sealing contact with said sealing surface.

30. An apparatus as defined in claim 29 in which said means for rockably mounting same bar comprises an aperture in said bar and a pin secured to said rotor and rockably disposed in said aperture.

31. An apparatus as defined in claim 8 in which each sealing element comprises a rigid elongated bar substantially arcuate in cross section, means for rockably mounting said bar on said rotor and a compression spring engaging said rotor and said bar to urge the same into sealing contact with said sealing surface.

32. An apparatus as defined in claim 8 in which each sealing element comprises an elongated bar substantially arcuate in cross section, means for rockably mounting said bar on said rotor and a compression spring engaging said rotor and said bar to urge the same into sealing contact with said sealing surface.

33. An apparatus as defined in claim 8 in which each sealing element comprises an elongated bar, means for rockably mounting said bar on said rotor and a compression spring engaging said rotor and said bar to urge the same into sealing contact with said sealing surface.

34. An apparatus as defined in claim 33 in which said rotor is provided with an outwardly extending flange and a pin secured to said flange serving to receive and guide said compression spring.

35. An apparatus as defined in claim 33 in which said means for rockably mounting said bar comprises an aperture in said bar and a pin secured to said rotor and rockably disposed in said aperture.

36. In a regenerative air preheater comprising two main parts, a first part providing stationary structure comprising a cylindrical casing and end plates having inlet and outlet openings for flow of gas and air respectively, the second part comprising a rotor mounted within said stationary structure, said rotor having an outer peripheral shell and being provided with radial partitions forming compartments with heat transfer material disposed in said compartments, and sealing means comprising a plurality of rigid sealing elements pivotally mounted on one of said main parts to have rocking movement relative to both of said parts and to bear against cooperating sealing surfaces on the other of said main parts, said sealing means providing seals between said shell and said partitions of the rotor on the one hand and said stationary structure on the other hand and located to bear against cooperating sealing surfaces on the other of said main parts, and biasing means associated with said rockably mounted sealing elements for urging the same into yieldable rocking contact with their cooperating sealing surfaces.
